UNITED STATES PATENT OFFICE.

GEORGE H. THORNTON, OF PATTERSON, ILLINOIS.

APPARATUS FOR USE IN PACKING FRUIT AND THE LIKE.

Application filed October 23, 1926. Serial No. 143,658.

This invention relates to apparatus for use in packing fruit and the like and it is primarily an object of the invention to provide an apparatus for removing a shell-like member or form from a basket or container employed in the packing operation.

Another object of the invention is to provide an apparatus of this kind for removing a shell-like member or form from a basket or container employed in a method of packing fruit, said means embodying a pulling mechanism engageable with the member or form and for holding the basket or container against strain imposed upon the member or form.

An additional object of the invention is to provide an apparatus of this kind adapted for use in connection with a method of packing fruit embodying a facing plate and a shell-like member or form wherein the apparatus operates to remove the form from within the basket or container comprised in the pack and which also serves to hold the facing plate against displacement during such removal of the member or form.

The invention consists in the details of construction and in the combination and arrangement of the several parts of my improved apparatus for use in packing fruit and the like whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view partly in elevation and partly in section illustrating an apparatus constructed in accordance with an embodiment of my invention in working arrangement, a second position of certain of the parts being indicated by broken lines;

Figure 2 is a view on a reduced scale partly in top plan and partly in section of the bench as herein employed;

Figure 3 is a detailed sectional view illustrating certain features of the form or shell-like member;

Figure 4 is an enlarged fragmentary sectional view illustrating in detail a portion of the apparatus and an assembly of the

pack, a second position of the form or shell-like member being indicated by broken lines;

Figure 5 is a view in top plan of the form or shell-like member as herein disclosed;

Figure 6 is a fragmentary view in elevation of the form or shell-like member;

Figure 7 is a fragmentary view partly in section and partly in side elevation of one of the double hooks and the lever with which it is associated;

Figure 8 is a view in front elevation of a double hook.

As disclosed in the accompanying drawings, F denotes a shell-like member or packing form comprising an elongated band 1 of saw blade steel or equivalent material, light in weight and easily bent or flexed to conform to the shape of the open end of a basket B or kindred receptacle. This band 1 has extending laterally therefrom the longitudinally spaced elongated fingers or blades 2.

The band 1 is adapted to be snugly engaged or formed within an annular ring 3 of a diameter substantially equal to the inside diameter of the basket B or the like, said band 1 being held to the ring 3 by rivets 4 or the like. The inner face of the applied band 1 has secured thereto by the rivets 4 or the like a plurality of inwardly disposed brackets 5 preferably four in number and equidistantly spaced to serve as a retaining means for the facing plate P to be hereinafter more particularly referred to.

The ring 3 has its upper marginal portion defined by an inwardly disposed strengthening or reinforcing flange 6 and said ring at diametrically opposed points is provided with pairs of upstanding lugs 7. Each pair of these lugs 7 is connected by a pin 8 disposed through the lugs to provide a connecting or attaching medium. The facing plate P has one face α dished or concaved and this plate is adapted to fit snugly within the form F in close contact with the brackets 5 hereinbefore referred to.

In packing a basket B or the like with fruit, the form F is placed upon a bench A with the blades 2 upwardly disposed. The facing plate B is then placed within the form F with its concave face α uppermost. A corrugated pad or the like may then be disposed upon said face α of the plate P. A layer of selected fruit is then placed upon

the concave face *a* of the plate *P* or the pad thereon, if used, and a strap *S* is then tightly fitted around the form *F*, say about three inches below the upper ends of the 5 blades *2*, said strap forcing said blades inwardly or packing the same so that the top of the form placed upon the bench *A* will be contracted to have the diameter of the upper portion of the form *F* substantially 10 the same as the diameter of the bottom of the basket *B* or container to be filled. The form *F* is then filled with fruit and leveled off about one inch above the top of the form. The basket or container *B* is then placed 15 over the upper portion of the filled form and after the strap *S* has been removed, the basket or container *B* is then forced down over the form *F* until the bottom of the basket is substantially in close contact with the 20 uppermost layer of fruit and the basket is then inverted to bring the same into its normal position.

When inverted or in its normal position just referred to, the basket *B* is arranged 25 below a top or head beam *9* disposed diagonally and laterally across an end portion of the bench *A* and supported at a desired position thereabove by the uprights or standards *10* suitably secured to opposite sides of 30 the bench *A* and at points spaced lengthwise of the bench. At its central portion the top or head beam *9* has bolted or otherwise secured thereto a pair of depending irons or brackets *11* between which is pivotally held by the pin *12* or the like the upper end portion of an elongated rod or member *14*.

The opposite or lower end portion of the rod or member *14* has bolted or otherwise secured thereto the outstanding irons or brackets *15* substantially coplanar with the adjacent lower end of the member or rod *14*. These irons or brackets *15* are secured by bolts or the like to the central portion of a plate or block *16* preferably of wood. 40

After the basket or container *B* has been inverted or returned to normal position it is slightly tilted to permit the member or rod *14* to be swung to bring the plate or block *16* to the central portion of the facing plate *P*. 45

The upper margin or edge of the basket or container *B* then has operatively engaged therewith the upstanding clamping members 50 55 60 65 17 pivotally connected with the bench *A* at opposite sides thereof, the pivoted portions of these clamping members being provided with inwardly directed arms *18*, the extremities of which being operatively engaged, as at *19*, with the inner end portion of a substantially horizontally disposed operating lever *20*. This lever *20* at a desired point intermediate its ends is pivotally engaged, as at *21*, to the bench *A*. By pulling up on the outer end portion of the lever *20* the clamping members *17* are caused to have effective

engagement with the upper portion or edge of the basket or container *B* to hold the basket or container *B* firmly to the bench *A*.

The member or rod *14* at a predetermined point above its lower end has bolted or otherwise attached at the opposite faces thereof the plates *22* each in the form of an inverted *T* whereby spaced arms *x* project in opposite directions beyond the member or rod *14*.

Pivots connected, as at *23*, between each pair of arms *x* is an end portion of a jack lever *24* and carried by each of these levers *24* is a double hook member *H* for engagement with a pin *8* hereinbefore referred to so that upon upward swinging movement of each of said levers the form *F* will be pulled out or withdrawn.

After the form *F* has been withdrawn, the levers *24* are held in their raised position by the hook members *H* carried by the member or rod *14* and said member or rod *14* is swung to one side of the filled basket or container *B* permitting the ready removal of the facing plate *P* to permit the desired application of a conventional basket or container lid or top.

The form *F* can be readily disengaged from the hook members *H*. This removal of the form *F* from the hook members *H* may be done immediately after the member or rod *14* has been swung to one side or later as preferred.

Each of the double hooks *H* comprises an intermediate connecting member *25* which engages a lever *24* from above and is received within a box plate *26* arranged upon the upper face of the lever *24* and held therein by a top plate *27*.

While I do not desire to limit myself to this connection, I find in practice that the bench *A* should be preferably five feet long, sixteen inches high and eighteen inches wide and supported at each corner portion by a leg *28*.

From the foregoing description it is thought to be obvious that an apparatus for use in packing fruit and the like constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:—

1. In combination with a shell-like member for holding the content placed within a container with the member, and means en-

gageable with the member for withdrawing the member from the container after said member and its content has been placed within the container.

5 2. In combination with a container and a content holding form for use in packing the container, an apparatus for removing the form from the filled container comprising a bench, means for clamping the container to the bench, and means for exerting pull upon the form to remove the form from the filled container.

10 3. An apparatus for removing a form used in packing a container comprising a bench upon which the filled container is placed, an elongated rod positioned above the bench, means coacting with the upper portion of the rod for supporting the rod for swinging movement, a member resting upon the content of the container and with which the rod engages, and means carried by the rod and engageable with the form for withdrawing the form from the container.

15 4. An apparatus for withdrawing a form used in the packing of a container comprising a vertically disposed rod, means for pivotally supporting said rod, and means carried by the rod and engageable with the form for pulling said form from within the container.

20 5. An apparatus for withdrawing a form

used in the packing of a container comprising a vertically disposed rod, means for pivotally supporting the rod, a lever pivotally engaged with the rod, and means carried by the lever and engageable with the form for withdrawing the form upon swinging movement of the lever in one direction. 35

6. An apparatus for withdrawing a form used in the packing of a container comprising a vertically disposed rod, means for pivotally supporting the rod, a lever pivotally engaged with the rod, means carried by the lever and engageable with the form for withdrawing the form upon swinging movement of the lever in one direction, and means for holding the lever against movement in the opposite direction. 40

7. An apparatus of the class described comprising an elongated member, means for supporting the same for swinging movement, and a pulling medium carried by the elongated member. 45

8. An apparatus of the class described comprising an elongated member, means for supporting the same for swinging movement, oppositely directed levers pivotally engaged with the elongated member, and an attaching means carried by each of the levers. 50

In testimony whereof I hereunto affix my signature.

GEORGE H. THORNTON.
